Application October 25, 1950, Serial No. 192,094

4 Claims. (Cl. 84—1.2)

This invention relates to electrical musical instruments and more particularly to electronic instruments of the organ type.

Electrical instruments of several different types have been proposed in which electric currents are generated and are mixed and controlled and used to drive a loudspeaker. Such instruments necessarily involve complications in the generation and control of the currents to produce the desired flexibility of operation.

It is a primary object of the present invention to provide an electrical musical instrument which involves a minimum number of parts and yet provides extremely great flexibility and versatility in operation.

Another object is to provide an electrical musical instrument in which tone currents falling in different selected frequency ranges can be variably attenuated in the output circuit. This not only enables the tonal quality to be controlled but also enables a desired balance or taper to be achieved with a minimum of complications.

Still another object is to provide an electrical musical instrument in which tone currents of different character are individually controlled and are mixed in selected intensities to produce different tonal effects. According to one feature certain of the tone currents may be filtered or attenuated to change their wave form, thereby further to increase the tonal resources of the instrument.

The above and other objects and advantages of the invention will be more readily apparent from the following description when read in connection with the accompanying drawing, in which:

Figure 1 is a partial circuit diagram of an electrical musical instrument embodying the invention;

Figures 2 and 3 are partial simplified diagrams illustrating modified forms of base and treble controls; and

Figure 4 is a partial simplified diagram showing different forms of tone control circuits.

In the instrument as shown in Figure 1, the tone currents are generated by oscillators of a type more particularly shown and described in our co-pending application Serial No. 188,990. It will be understood that there is a separate oscillator for each note desired, so that a complete instrument may embody 85 or more oscillators. Each oscillator as illustrated, comprises a triode vacuum tube 10 whose plate is connected through a series resistor 11 and keying switch 12 to a +B source indicated at 13. The plate may also be connected to ground through a condenser 14 which cooperates with the resistor 11 to control the attack and release characteristics of the instrument. The cathodes are connected through coil 24 and through a resistor 17 to ground, thereby to complete a circuit with the tube plates. The cathodes of the several tubes are connected through the resistor 17 to ground in parallel, and each of the oscillators has its own mixer resistor, as indicated at 18, 18' and 18'', etc. Preferably the oscillators are divided into banks of an octave or more, as desired, with the mixer resistors 18, 18' etc., connected to ground through a common condenser 19.

Pulse currents are developed in this circuit and are

2

derived therefrom by means of a transformer having a primary winding 21 connected across the resistor 17 and a secondary output winding 22.

Each of the oscillators also develops a sine wave current which is derived from a connection 23 between the mixer resistors 18 and the condensers 19, as shown. The cathodes of the tubes are connected to taps on coils 24 shunted by condensers 25 and forming tank circuits for the oscillators. The tank circuits are connected through grid condensers 26 to the control grids of the tubes, which are also connected through resistors 27 to a point between resistor 15 and condenser 16, as shown. The resistor 15 is connected to the +B source and through the condenser 16 to the high side of resistor 17.

The several oscillators or groups of oscillators are preferably divided into banks, and the connections 23 of each group of banks may be connected through resistors 28 to flute buses 29. The flute tones from the several buses are mixed in a mixer unit and supplied simultaneously therefrom to the output circuit. As shown, two buses are contemplated and the currents therefrom are mixed by a mixer, including a pair of triode tubes 31 whose plates are connected to a +B supply through load resistors 32, and are interconnected through series resistors 33. The cathodes of the tubes 31 are grounded through a cathode resistor 34 and the grids thereof are connected to the flute bus bars through connections, one of which is shown at 35. The mixed flute tones are taken off from a point between the two resistors 33 through a condenser 36 and resistor 37.

Tremolo currents may be supplied to the generators from a tremolo generator 38 connected through a transformer 39 to a plurality of series connected resistors 41. A tap connected from the +B source to the primary of the transformer 39 supplies power to the tremolo generator. The grids of the first set or bank of oscillators may be connected directly to the lower end of the secondary of transformer 39 through their grid resistors 27, as shown. Succeeding banks of oscillators may have their grids connected to points between the successive resistors 41 so that different amounts of tremolo voltage will be supplied to the different banks of oscillators. In this way the amount of tremolo or the tremolo balance throughout the entire keyboard is controlled as desired. The top end of the series resistors 41 is returned to ground, as illustrated generally by the dotted connection 40, to provide the necessary return from the grids of the oscillator tubes 10 to their respective cathodes.

For the output of the instrument the pulse and sine wave or flute tones are mixed and are supplied through an amplifier 42 to a loudspeaker 43. The amplifier is preferably connected to the output circuit of the instrument through a potentiometer 44 controlled by an expression pedal to regulate the overall amplitude of the instrument. The output circuit is supplied from a mixer, including a pair of tubes 45 whose cathodes are grounded through a resistor 46 and whose plates are connected to a +B source through plate resistors 47. The plates of the tubes are interconnected by resistors 48, and the output circuit is connected to a point between the resistors 48 through a blocking condenser 49.

The flute signals from the flute mixer are supplied to the grid of one of the tubes 45. To control the amount of flute tone in the output a control circuit is inserted in the connection and, as shown, comprises three resistors 51 connected in series from the flute mixer output to ground with switches 52, by means of which all or any portion of the resistors 51 can be selected. In the position shown the flute tone will be cut off or at minimum volume. When the right hand switch is thrown to the right the resistors 51 are all in the circuit so that maximum flute tone is provided. By opening and clos-

ing the switches 52, more or less of the resistors can be cut in to control the flute tone volume as desired.

The pulse tone developed in the transformer winding 22 is utilized to produce both a string and a reed effect. For the string effect the pulse tone is used substantially as generated, and its volume is controlled by a unit similar to that described above for the flute tone control. As shown, the unit comprises a plurality of series resistors 53 connected between a center tap on the winding 22 and ground, and a series of switches 54 by means of which the resistors 53 can be cut into or out of the circuit. The string tone control circuit as shown is connected through a blocking resistor 55 to the grid of the other mixing tube 45.

To develop reed tones the pulses are filtered in a resonant circuit which includes an inductance coil 56 connected across the transformer winding 22 through a blocking resistor 57. More or less capacitance can be connected in parallel with the coil 56, and as shown for this purpose a plurality of condensers 58 are connected between one end of the coil 56 and ground through control switches 59. By opening and closing the switches 59 in proper sequence the tuning of the circuit can be varied to alter the wave form of the pulses differently and to control the volume of reed tone supplied to the circuit.

The mixed pulse and flute tones provided by the mixing tubes 45 are supplied through the output circuit to the amplifier. In order to control the taper of the instrument as well as to provide greater tonal contrast bass and treble control circuits are provided in the output circuit. As shown in Figures 1 and 2, the bass control comprises a condenser 61 in series in the output circuit, which is shunted by a variable resistance indicated at 62 in Figure 2. As shown in Figure 1, the variable resistance 62 may be provided by series resistors 62', which are selectively cut into and out of the circuit by switches 63. In this construction the condenser 61 offers less resistance to the high frequency tones than to the low frequency tones, so that the low frequency tones are attenuated to a greater extent than the high frequency tones by the resistor 62.

In the form shown in Figures 1 and 2 the treble tones are controlled by a capacitor 64 connected in shunt across the output circuit. As illustrated in Figure 1, this variable capacitor may comprise a pair of condensers 64' connected between the hot side of the output circuit and ground and cut into or out of the circuit by switches 65. By adjustment of the amount of capacity in shunt across the output circuit the high frequency tones may be bypassed to the desired extent without materially affecting the lower frequency or bass tones.

Figure 3 illustrates an alternative bass and treble control arrangement in which the tone generating source is indicated generally at 66 as supplying an output potentiometer 44'. The source 66 is connected through resistors 67, which may represent the internal resistance of the tubes and the circuit components to the potentiometer. To control the bass tones a variable inductance 68 is connected in shunt across the circuit variably to bypass the lower frequency currents without materially affecting the higher frequency currents. The high frequency or treble tones are controlled by a variable inductance 69 in series in the line which will exert a variable chocking effect on the high frequency currents without materially affecting the low frequency or bass notes.

It will be understood that in the complete instrument the usual keyboard involving one, two, or more manuals and a pedal board may be provided connected to control the different oscillators through the usual coupling circuits. These coupling circuits, together with the tone control provided to vary the intensities of the flute and string tones and the reed control circuit to provide different distinctive reed voices, give to the instrument an extremely large flexibility and enormous tonal resources.

Further, tonal effects can be achieved through the base and treble controls which will modify selectively the strengths of the different tempered harmonics without requiring the complications which would be necessary to change the amplitudes of the tone frequency generators. This control additionally enables the organist to accentuate a particular section of the manual, as, for example, to bring out a solo melody while other portions of the same manual or the other manuals may be attenuated for accompaniment without producing an abrupt point of change at some point in the keyboard. Through the use of these several controls an almost unlimited number of different musical effects and combinations are possible, so that a relatively simple instrument becomes capable of the flexibility of operation ordinarily possible only with relatively complicated and expensive instruments.

Additional pleasing effects can be produced and further versatility can be provided in the instrument through the use of resonant controls in the output circuit as indicated in Figure 4. As shown, a parallel resonant circuit is provided including an inductance coil 71 having a variable condenser 72 in parallel therewith across the output circuit. This will pass the signals at the resonant frequency and will attenuate signals both above and below the resonant frequency. Additionally a series resonant circuit including an inductance coil 73 with a variable condenser 74 in series therewith is connected across the output circuit. This circuit will provide greatest attenuation for signals at its resonant frequency and less attenuation of signals above and below resonance. The resonant circuits may be made effective or ineffective as desired by switches 75. It will be understood that these resonant circuits can be used in addition to the bass and treble control circuits described above.

The several controls in the output circuit enable a wide variety of interesting and useful musical effects to be obtained. For example, using only the flute tones and setting the couplers to borrow desired harmonics, it is possible by selecting the desired controls and adjusting them properly to duplicate most of the effects obtainable through tone synthesis without the complications involved in adjusting the amplitude of particular partials at the generators. By using mixtures of the flute and pulse tones and the output controls an almost endless variety of effects can be produced since the operator has full control of the harmonic structure of the tones.

While the invention has been shown and described in connection with one particular type of tone generators and with specific tone control circuits, it will be understood that this showing is illustrative only and is not to be taken as a definition of the scope of the invention, reference being had for this purpose to the appended claims.

What is claimed is:

1. An electrical musical instrument comprising a plurality of generators each including a first means to generate a sine wave current and a second means to generate a current rich in harmonics, a mixing device, a first circuit connecting the first means to the mixing device, an adjustable attenuating device in the first circuit variably to attenuate the sine wave currents, a second circuit connecting the second means to the mixing device, an adjustable attenuating device in the second circuit variably to attenuate the currents rich in harmonics, a third circuit connecting the second means to the mixing device, and elements in the third circuit at least one of which is adjustable, forming a resonant circuit to change the wave form of the currents rich in harmonics.
2. An electrical musical instrument comprising a plurality of generators each including a first means to generate a sine wave current and a second means to generate a current rich in harmonics, a mixing device, a first circuit connecting the first means to the mixing device, an adjustable attenuating device in the first circuit variably to attenuate the sine wave currents, a second circuit con-

necting the second means to the mixing device, an adjustable attenuating device in the second circuit variably to attenuate the currents rich in harmonics, a third circuit connecting the second means to the mixing device, elements in the third circuit at least one of which is adjustable, forming a resonant circuit to change the wave form of the current rich in harmonics, an output circuit connected to the mixing device, and adjustable attenuating devices in the output circuit selectively to attenuate currents having frequencies falling in a selected range.

3. An electrical musical instrument including in combination, generator means for generating sine wave currents of different audible fundamental frequencies and currents of different audible frequencies which are rich in harmonics, a mixing device, circuit means connecting said generator means to said mixing device and including a first circuit portion for applying said sine wave currents to said mixing device and a second circuit portion for applying said currents rich in harmonics to said mixing device, said first circuit portion including adjustable attenuating means, said second circuit portion including adjustable attenuating means and adjustable resonant means for selectively changing the wave form of the currents rich in harmonics, and an output circuit connected to said mixing device including adjustable impedance means selectively effective only for currents below a predetermined fundamental frequency in the audio range variably to attenuate the relatively low frequency currents in said output circuit corresponding to the bass notes, said output circuit including second adjustable impedance means selectively effective for currents above a predetermined fundamental frequency in the audio range variably to attenuate the relatively high frequency currents in said output circuit corresponding to the treble notes.

4. An electrical musical instrument comprising a plural. 35

ity of tone generators to generate currents of different fundamental audio frequencies, at least a part of said generators having a first output providing sine wave current and a second output providing current rich in harmonics, mixing means, circuit means selectively applying currents from said outputs of said generators to said mixing means, said circuit means including a first circuit portion connected to said first outputs of said generators and a second circuit portion connected to said second outputs thereof, said first circuit portion including adjustable attenuating means for attenuating said sine wave currents, said second circuit means including adjustable attenuating means and adjustable resonant means for changing the wave form of said currents rich in harmonics, an output circuit for said mixing means, a pair of adjustable filtering means connected to said output circuit and effective respectively only on tone currents having fundamental frequencies above and below predetermined values in the audible range variably to attenuate the high and low frequency currents respectively, and adjustable resonant filter means tuned to a frequency substantially the same as one of said fundamental audio frequencies selectively connected to said output circuit variably to attenuate currents whose frequencies fall in a selected range.
